US0D1104737S

(12) **United States Design Patent** (10) **Patent No.:** **US D1,104,737 S**
(45) **Date of Patent:** **** Dec. 9, 2025**

(54) **PACKAGING FOR CRAFT MATERIALS**

(71) Applicant: **Cricut, Inc.**, South Jordan, UT (US)

(72) Inventors: **Bridgid Cody**, Salt Lake City, UT (US); **Kelly Drum**, Hudson, NC (US); **Jodie Holdman**, West Jordan, UT (US)

(73) Assignee: **Cricut, Inc.**, South Jordan, UT (US)

(**) Term: **15 Years**

(21) Appl. No.: **29/992,087**

(22) Filed: **Mar. 5, 2025**

(51) **LOC (15) Cl.** 09-03

(52) **U.S. Cl.**

USPC **D9/418**; D9/432

CLAIM

The ornamental design for packaging for craft materials, as shown and described.

DESCRIPTION

FIG. 1 is a front, right, top isometric view of the packaging for craft materials;

FIG. 2 is a front, right, top isometric view of the packaging for craft materials in an open configuration;

FIG. 3 is a front, right, top isometric view of the packaging for craft materials in an open configuration showing an exemplary craft material partially within the packaging;

FIG. 4 is a front elevation view of the packaging for craft materials;

FIG. 5 is a rear elevation view of the packaging for craft materials;

FIG. 6 is a left side elevation view of the packaging for craft materials;

FIG. 7 is a right side elevation view of the packaging for craft materials;

FIG. 8 is a top plan view of the packaging for craft materials; and,

FIG. 9 is a bottom plan view of the packaging for craft materials.

The dot broken lines in the figures depict portions of the packaging for craft materials and environmental structure that form no part of the claimed design and the dot-dash broken lines immediately adjacent to the claim depict the bounds of the claimed design and form no part of the claimed design.

1 Claim, 5 Drawing Sheets
